UNITED STATES PATENT OFFICE.

DON A. PHELPS, OF CINCINNATI, OHIO.

PARCEL-CARRIER.

SPECIFICATION forming part of Letters Patent No. 423,696, dated March 18, 1890.

Application filed June 20, 1889. Serial No. 314,986. (No model.)

To all whom it may concern:

Be it known that I, DON ALANSON PHELPS, a citizen of the United States, residing at Cincinnati, in the county of Hamilton, State of Ohio, have invented certain new and useful Improvements in Parcel-Carriers, of which the following is a specification, reference being had to the accompanying drawings, forming a part thereof.

10 The object of my invention is to construct a parcel or package carrier in such a manner that the fastening-cords may be attached to and clamped in suitable spring fastening devices attached to the ends of a suitable handle without having to tie said cords, as will more fully hereinafter appear.

In the accompanying drawings, Figure 1 is a perspective view of my improved parcel-carrier in an operative position. Fig. 2 is a 20 top view of one portion of the split handle, showing one mode of connecting the spring fastening devices thereto. Fig. 3 is a perspective view, on an enlarged scale, of one of the spring fastening devices detached from the 25 handle.

My improved parcel-carrier is preferably constructed as follows: The handle A is composed of two longitudinal semi-cylindrical portions glued or otherwise suitably secured 30 together, one of said portions having in its inner flat surface the longitudinal grooves a a and cross-grooves a', as shown in Fig. 2.

The spring clamp or fastening devices are each preferably formed from one continuous 35 piece of spring-wire, and are so bent from the center of each piece as to form the parallel portions b b, end portion b, eyes B B, downward extensions C C, loops D D, upturned portions E E, the latter terminating in the 40 hooked portions e e, as shown. The parallel portions C and E of the fastening device form a clamp to retain the fastening-cords between them, as will more fully hereinafter appear. The parallel portions b b and end portion b

45 of each spring-fastening is placed in the parallel and cross grooves in one of the handle portions, as shown in Fig. 2, after which the other portion of the handle is glued or otherwise suitably secured thereto, thus serving to 50 retain said spring-fastenings to place in the ends of the handle without danger of becom-

ing disengaged therefrom or turning. One end of each fastening-cord F is passed through the eyes B, as shown in Fig. 1, and a knot tied in the end thereof, which knot bears against one of said eyes, preventing said cord from being pulled through the eyes. The other end of said cord is passed through said eyes in an opposite direction to provide a draw-loop for the parcel.

The operation of my device is as follows: The fastening-cords are made of any desired length, and when secured in the eyes of the fastening device, as aforescribed, form a loop, which is slipped over each end of the 65 package or parcel to be carried, when the free end of the cord is drawn up until the loops are taut around the package, after which said free end of each cord is passed under one of the hooks e and pressed down between the 70 clamp portions C and E, as shown. The clamp portions, in connection with the two angles formed in cords at the hooks e and eyes B, serve to securely retain the free ends of the 75 cords from slipping, and in this manner heavy packages may be securely carried.

While it is preferred to connect the spring fastening devices in the handle, as set forth, any other suitable means may be employed for making such connection.

If desired, a suitable base may be connected to the looped portions D, by means of screws or rivets, when the parcel-carrier will answer all purposes of the ordinary shawl-strap.

The advantages of my device are apparent. 85 It is simple in construction and effective in operation.

By the use of said device all tying of cords or buckling of straps is dispensed with, thus saving much time.

The device is cheap of manufacture and will answer all purposes of any parcel-carrier, and when provided with a suitable base, as aforementioned, will answer all purposes of a shawl-strap.

What I claim as new, and desire to secure by Letters Patent, is—

1. A parcel-carrier consisting of the spring-wire fasteners bent to form the retaining portions b, eyes B, parallel clamp portions C and E, base-loops D, and hooks e, the parallel clamp portions being bent downward and up-

ward from the eyes at an angle to the portions *b*, and the base-loops *D* being bent outward at an angle to the clamp portions, the top of the portions *E* terminating in hooks *e*, the whole being attached to a suitable handle, as set forth.

2. A parcel-carrier having the spring-fasteners bent, as shown, in combination with the split handle, one portion of said handle hav-

ing in its flat inner face the longitudinal and cross grooves *a a' a'*, the parallel portions *b*, and end portion *b* of each fastener resting in said grooves, and suitable means for fastening the two portions of said handle together.

DON A. PHELPS.
